UNITED STATES PATENT OFFICE.

BERT EUGENE HILL, OF NATCHEZ, MISSISSIPPI, ASSIGNOR TO NATIONAL BOX COMPANY, OF CHICAGO, ILLINOIS, A CORPORATION OF ILLINOIS.

APPARATUS FOR MAKING BOX BLANKS.

Application filed September 17, 1920. Serial No. 411,010.

To all whom it may concern:

Be it known that I, BERT EUGENE HILL, a citizen of the United States, and a resident of Natchez, in the county of Adams and 5 State of Mississippi, have invented certain new and useful Improvements in Apparatus for Making Box Blanks, of which the following is a specification, reference being had to the accompanying drawings.

10 My invention relates to the manufacture of box blanks of the type comprising thin boards or panels secured by staples to longitudinally-extending cleats, and has for its object to provide an improved machine 15 which will operate automatically to assemble the cleats and panels in proper relation to each other and deliver them to the stapling mechanism, so that the machine may be successfully operated by unskilled 20 labor without risk of personal injury, while at the same time a better and more uniformly-stapled blank will be produced, and there will be little or no waste of wire by 25 reason of improperly-timed operations of the stapling mechanism. The preferred means by which I have accomplished my object are illustrated in the drawings and are hereinafter specifically described. That 30 which I believe to be new and desire to cover by Letters Patent is set forth in the claims.

In the drawings,—

Fig. 1 is a side view of a blank making machine, more or less diagrammatic and partly in section;

35 Fig. 2 is a top view of one of the frames upon which the parts of the blank are positioned, and by which they are held for the stapling operation;

Fig. 3 is a cross-section taken on line 3—3 40 of Fig. 2;

Fig. 4 is a top view of a completed blank;

Fig. 5 is a central longitudinal sectional view through the rack by which the frame with the blank parts thereon is fed to the 45 stapling mechanism;

Fig. 6 is a fragmentary view showing a portion of the frame illustrated in Fig. 2 but with the cleat engaging springs compressed inwardly to permit the ready insertion of the cleats thereinto; and

Fig. 7 is a view of a complete box embodying two blanks of the type shown in Fig. 4 and two other blanks of more or less similar construction.

55 Referring to the drawings,—15 indicates

a frame in which is mounted a driving shaft 16. 17 indicates an automatically acting stapling device of any approved type operatively connected by the use of any suitable driving mechanism with the shaft 16, the 60 stapling mechanism being adapted to deliver and drive a wire staple at each actuation of the device. In a machine designed to produce a blank like that shown in Fig. 4, two staple driving mechanisms of the type 65 shown, arranged side by side at the proper intervals for driving two rows of staples, will be provided. Shafts 18 and 19 are suitably mounted in the framework, supporting drums 20 and 21 respectively upon which 70 is mounted an endless belt 22 of leather or other suitable material. Suitable means may be provided if desired for supporting the upper course of the belt 22 between the drums 20 and 21. The belt 22 is driven so 75 that its upper course travels toward the right as viewed in Fig. 1, by means of a sprocket wheel 23 mounted upon the shaft 19, and rotated intermittently in a clockwise direction by mechanism which will be 80 hereinafter described. A hopper or magazine 24 adapted to contain a plurality of cleats 25 is mounted at each side of the machine above the belt 22 for feeding the 85 cleats 25 to frames 26 (see Fig. 2) as such frames are carried underneath the hopper by the belt 22. A similar hopper 27 disposed transversely of the belt, holding a plurality of panels 28, is adapted to feed the panels 90 to said frames so that their end margins 95 overlie the cleats in position to be stapled thereto, as hereinafter described.

With the belt 22 being driven and with the stapling mechanism 17 being actuated at intervals, a frame is placed in position 100 upon the belt 22 at the left as illustrated in Fig. 1 so as to be carried forward by the belt under the hopper 24. As the frame passes underneath the hopper two of the cleats 25 are automatically fed into position 105 as shown in Fig. 6. As the frame passes beneath the hopper 24, another frame 26 is placed upon the belt 22 with its forward edge in contact with the frame 26 immediately ahead of it. As the frame containing the cleats 25 passes next under the hopper 27, pawls 28 are automatically deposited in position upon the cleats 25. When the frame 26 reaches the right-hand end portion 110 of the machine as shown in Fig. 1, a posi-

tively acting forwarding device feeds the frame forward intermittently under the stapling devices 17 which serve to connect the panels with the cleats by a plurality of 5 staples 29 thereby forming the blank shown in Fig. 4.

Each of the frames 26 comprises longitudinally-extending bars between which the cleats 25 are placed, as is best shown in Fig. 10. 6. Flat springs 31 are mounted upon the frames in position to engage the inner edges of the cleats 25 for pressing them against the inner edges of the outer longitudinal bars of the frame. For displacing the springs 31 15 as the frame moves forward with the belt 22, I have provided a pair of discs or wheels 32, (see Figs. 1 and 6) which are so positioned as to engage the springs at the time when the cleats are to be placed in position. As 20 is shown in Fig. 1, each of the discs 32 is revolvably mounted upon one arm of a lever 33, the other arm of which is provided with a weight 34 adjustably mounted thereon. As will be readily understood, as the frame 25 26 moves toward the right as seen in Fig. 2, the springs 31 are moved temporarily out of their normal position into the position shown in Fig. 6, in which position they are held by the discs 32 until the frame has advanced sufficiently for clearing the springs 30 from contact with the discs.

The hopper 24 is so arranged that, when the frame 26 passes thereunder, the rear cross-bar of the frame engages the rear end 35 of the lowermost cleat in the hopper so as to cause such lowermost cleat to pass forward with the frame and to drop into position therein. As will be readily understood, the cross-bar at the forward end of the 40 frame does not engage the rear end of the cleat for the reason that such forward cross-bar is in close engagement upon the belt 22 with the rear cross-bar of the next preceding frame 26, as is clearly shown in Fig. 1. The 45 hopper 24 is provided at its forward end with a pivotally mounted arm 35 which is held yieldingly in normal position as shown in Fig. 1 by means of a spring 36 mounted upon a rod 37 which is pivotally connected 50 with the arm, the spring 36 having a bearing at its forward end against a lug 38 fixedly mounted in position, the rod 37 being slidably mounted in a suitable opening in the lug. As the lowermost cleat 25 is moved 55 forward with the frame 26 as above described, the arm 35 is displaced toward the right in said Fig. 1 against the action of the spring 36. When, however, the forward end of the cleat is carried out of contact with the lower end of the arm 35 by the forward 60 movement of the cleat, the arm 35 is caused to swing smartly backward by the action of the spring 36, bringing the lower end of the arm 35 into contact with the lowermost 65 remaining cleat 25 in the hopper 24,

serving to push such cleat backward slightly into the position of the lowermost cleat 25 as shown in Fig. 1. In case the cleat does not readily fall into proper position within the frame 26, a spring pressed roller 39 at 70 a short distance in advance of the hopper 24 serves to apply the necessary pressure to the cleat for forcing the cleat into normal position. As is best shown in Fig. 2 the frame 26 is provided with a plurality of short 75 transverse strips 40 which serve as spacers for the panels of the blank. As the frame 26 is carried forward by the belt 22 under the hopper 27, each of the several cross strips 40 of the frame in rear of the foremost one of such strips engages the rear edge of a panel 28 so as to push such panel forward for causing it to drop into position between the strips 40 as is shown at the right in Fig. 1, a spring pressed roller 41 being 80 provided for applying the necessary pressure for forcing the panel 28 into place. The hopper 27 is also provided with an arm 42 pivotally mounted thereon pressed by a spring 43 into normal position as shown in 85 Fig. 1, the spring 43 being mounted upon a rod 44 similar to the rod 37 and having a bearing against a fixedly disposed lug 45. Inasmuch as the spring pressed arm 42 operates in the same manner as that already described in connection with the arm 35, it is believed to be unnecessary to describe the 90 same further herein.

The means for giving the belt 22 the desired intermittent motion, comprises an eccentric 46 mounted upon the driving shaft 16 and connected by means of a rod 47 with an arm 48 carried by a rock-shaft 49. The connection between the rod 47 and the arm 48 is adjustable by the provision of a slot 50 whereby the extent to which the shaft 49 is rocked upon the rotation of the shaft 16 may be varied slightly. An arm 51 depending from the rock-shaft 49 is pivotally connected at its lower end portion to the forward end of a link 52, the connection of the link with the arm being effected by the use of any one of a plurality of holes 53 in the said arm. At its rear end the link 52 is pivotally connected to a block 54 which is 100 swingingly mounted by means of arms 55 about a shaft 56. The block 54 carries a pawl 57 which is adapted to engage the teeth of a ratchet wheel 58 fixedly mounted upon the shaft 56. As will be readily understood, as the link 52 is reciprocated back and forth by the arm 51, the pawl 57 serves to give the ratchet wheel 58 an intermittent motion in clockwise direction as shown in Fig. 1. Through the medium of the shaft 56, a 105 sprocket gear 59 mounted thereon, and a sprocket chain 60 connecting the sprocket gear 59 with the sprocket gear 23, the intermittent motion of the ratchet wheel 58 is 110 transmitted to the sprocket gear 23, the 115 120 125 130

shaft 19, the drum 21 and the belt 22. By the adjustment of the connection between the link 52 and the arm 51, the speed of the belt 22 is regulated with respect to the motion of the rock-shaft 49 as may be desired.

The rock-shaft 49 is also provided with an upwardly-extending arm 61 fixedly mounted thereon, the arm 61 having pivotally mounted upon its upper end portion a bar 62 the forward end of which is connected by means of a spring 63 with a portion of the arm 61 at some little distance below the pivotal connection of the bar therewith whereby the spring 63 serves to hold the rear end 15 of the bar 62 yieldingly upward. At the rear end portion the bar 62 is provided with a ratchet tooth 64 of any suitable type which is adapted to engage one of the teeth of a rack-bar 65 carried in central position by 20 each of the frames 26 on the under face thereof. As is best shown in Fig. 5 the rack bar 62 is in the form of a strip of sheet metal having teeth stamped out of the body of the metal, and I prefer to use this form of 25 rack bar. As one of the frames 26 is fed forward by the belt 22 by yielding frictional engagement therewith, and is brought into position to have the rack 65 carried thereby engaged by the reciprocatory bar 62, the 30 frame 26 is drawn out of contact with the belt by an intermittent motion, the ratchet tooth 64 being adapted to advance the frame step by step as the tooth engages successively 35 the teeth of the bar 65. As will be appreciated by a comparison of Figs. 4 and 5, the teeth of the rack-bar 65 are spaced in 40 position with respect to each other to correspond to the positions at which it is designed to have the staples 29 located in the completed blank. By the proper arrangement 45 of the teeth along the bar 65, the spacing of the staples can be regulated as may be desired. It will be understood that if desired either a greater or smaller number 50 of staples might be inserted in each of the panels 28 in lieu of the three staples in each end of each of such panels as is shown in Fig. 4, this result being attained by making a correspondingly different arrangement 55 and spacing of the teeth upon the rack-bar 65.

As will be readily understood, when a frame 26 being carried by the belt 22 comes in contact with another frame 26 being carried forward by the positively-acting forwarding means comprising the toothed member 64, the frame in contact with the belt is adapted to slip with respect to the belt so as not to interfere with the regular 60 spacing of the staples being driven in the blank passing under the stapling device.

Means is provided for automatically stopping the operation of the machine in case the operator fails to place one of the frames 65 26 in position on the belt 22 adjacent to the

frame passing under the hopper 24. This means comprises a roller 66 mounted upon the upper end of a lever 67 the lower end of which is connected by a spring 68 with a suitable portion of the framework 15, the 70 spring being adapted normally to swing the lever 67 in clockwise direction as seen in Fig. 1, for carrying the roller 66 upward into the path of the frames 26. As will be appreciated, so long as the frames 26 are 75 placed in proper time upon the belt 22 as the belt carries the frames forward successively, the roller 66 will be held down against the action of the spring 68. When, however, the frame 26 against which the 80 roller 66 bears is moved forward out of contact with such roller, and the operator fails to place another frame in position so as to come promptly into contact with the roller 66, the spring 68 is free to move the 85 lever 67 in clockwise direction in said Fig. 1. The lever 67 is connected at its lower end to a link 69 which is pivotally connected to the lower end of the lever 70, the 90 upper end of which is pivotally connected to a link 71 which is pivotally connected at its forward end to an arm 72 swingingly mounted about the shaft 56. The arm 72 has mounted thereon another arm 73, the outer end of which is provided with a shield 95 74 curved about the ratchet wheel 58. When the lever 67 is moved in clockwise direction as above described, the link 71 is moved forward carrying the arms 72 and 73 and the shield 74 in clockwise direction in said figure, serving to place the shield 74 into position between the pawl 57 and the teeth of the ratchet wheel 58, and serving thus to stop the intermittent motion of the belt 22. A stop 75 is mounted in suitable position for limiting the movement of the lever 70. 100

While I prefer to use bearing parts upon the levers 33 in the form of discs or wheels revolvably mounted thereon, such as the bearing discs 32, it will be understood that I do not wish to be limited to that precise form of structure except as hereinafter specifically claimed. 110

As will be readily understood, in the construction shown for making the blank of Fig. 4, two of the hoppers 24 will be used arranged side by side for feeding a cleat to the frame 26 at each side thereof, but I do not wish to be restricted to the use of any particular number of such hoppers and feeding mechanisms except as may be hereinafter specifically claimed. 120

What I claim as my invention and desire to secure by Letters Patent, is— 125

1. In a machine for making box blanks, the combination of stapling mechanism, conveying mechanism for conducting frames containing blank parts assembled in position for stapling to said stapling mecha- 130

- nism, and mechanism for advancing said frames past said stapling mechanism, the latter mechanism being adjustable independently of the said conveying mechanism to 5 vary the position or number of the staples.
2. In a machine for making box blanks, the combination of stapling mechanism, means for frictionally engaging and conducting frames containing box blanks assembled in position for stapling to said stapling mechanism, and separate means for moving such frames past said stapling mechanism.
3. In a machine for making box blanks, 15 the combination of stapling mechanism, means for frictionally engaging and conducting frames containing box blanks assembled in position for stapling to said stapling mechanism, and means for varying 20 the progress of said frames past said stapling mechanism independently of said conducting means.
4. In a box blank making machine, the combination with stapling mechanism, of a 25 horizontally disposed conveyor leading to such stapling mechanism, separate frames adapted to be supported and conducted by said conveyor, said frames being arranged to receive cleats and panels assembled in 30 position for stapling, and magazines for supplying cleats and panels to said frames as they are conducted past said magazines by said conveyor.
5. A machine for making box blanks comprising a stapling device, a frame adapted 35 to hold in position the parts of a blank, a rack-bar centrally mounted on said frame, means engaging said rack bar from below for feeding said frame under said stapling 40 device, and conveyor mechanism for conducting said frame to said rack-bar engaging means.
6. A machine for making box blanks comprising a stapling device, a frame adapted to 45 hold in position the parts of a blank, a rack-bar extending longitudinally of said frame in central position on the lower face thereof, reciprocal actuating means adapted to engage said rack-bar from beneath for feeding said frame under said stapling device, and conveyor mechanism for conducting 50 said frame to said rack-bar engaging means.
7. A machine for making box blanks comprising a stapling device, a frame adapted 55 to hold in position the parts of a blank, means frictionally engaging said frame for moving it approximately to said stapling device, and positively-acting means for feeding said frame under said stapling device.
- 60 8. A machine for making box blanks comprising a stapling device, a frame adapted to hold in position the parts of a blank, means for delivering the blank parts to said frame, means frictionally engaging said frame for moving it until it reaches said stapling device and positively-acting means for feeding said frame under said stapling device.
9. A machine for making box blanks comprising a stapling device, a frame adapted 70 to hold in position the parts of a blank, means frictionally engaging said frame for moving it toward said stapling device, means adapted automatically to deliver the blank parts to said frame as it is advanced 75 by said means, and positively-acting means for feeding said frame under said stapling device.
10. A machine for making box blanks comprising a stapling device, a frame adapted 80 to hold in position the parts of a blank, means frictionally engaging said frame for moving it toward said stapling device, means adapted automatically to deliver cleats to said frame as it is advanced by said 85 means, other means adapted automatically to deliver panels to said frame over-lying said cleats, and positively-acting means for feeding said frame under said stapling device.
11. A machine for making box blanks comprising a stapling device, a frame adapted 90 to hold in position the parts of a blank, an endless belt for moving said frame forward by friction toward said stapling device, means adapted automatically to deliver the blank parts to said frame as it moves forward, and positively-acting means for feeding said frame under said stapling device.
12. A machine for making box blanks comprising a stapling device, a frame adapted 95 to hold in position the parts of a blank, an endless belt upon which said frame rests and is carried forward by frictional engagement toward said stapling device, and positively-acting means for feeding said frame from said belt under said stapling device.
13. A machine for making box blanks comprising a stapling device, a frame adapted 100 to hold in position the parts of a blank, means for moving said frame forward by friction toward said stapling device, means adapted automatically to deliver the blank parts to said frame in position to be stapled 105 as the frame moves forward, and positively-acting means for feeding said frame forward by a step by step movement under said stapling device to correspond to the desired spacing of the staples in said blank.
14. A box blank making machine comprising a frame adapted to receive the blank parts, means for supporting said frame in a substantially horizontal position and moving it forward, means for supplying blank parts to said frame as it is advanced, yielding means mounted on said frame adapted 115 normally to press said parts against said

frame and mechanism for displacing said yielding means to permit the ready insertion of said blank parts in said frame.

15. A box blank making machine comprising a frame adapted to receive the blank parts, means for supporting said frame in a substantially horizontal position and moving it forward, means for supplying blank parts to said frame as it is advanced, yielding means mounted on said frame adapted normally to press said parts against said frame, automatically acting means for delivering the blank parts to said frame as it moves forward, and automatically acting mechanism for displacing said yielding means when said frame is in position to receive said blank parts, to permit the insertion of the blank parts.

16. A box blank making machine comprising a frame adapted to receive the blank parts, means for supporting said frame in a substantially horizontal position and moving it forward, means for supplying blank parts to said frame as it is advanced, springs mounted on said frame and normally extending into the position to be occupied by certain of said blank parts, and mechanism acting automatically as the frame moves into position to receive said blank parts for displacing said springs to permit the insertion in said frame of said blank parts.

17. A box blank making machine comprising a frame adapted to receive the blank parts, means for moving said frame forward, flat springs mounted on said frame and extending diagonally outwardly into the position to be occupied by certain of said blank parts, and means engaging said flat springs on the outer faces thereof adapted to press the springs inwardly so as to permit the insertion of said blank parts as the frame moves forward.

18. A box blank making machine comprising a frame adapted to receive the blank parts, means for moving said frame forward, flat springs mounted on said frame and extending diagonally outwardly into the position to be occupied by certain of said blank parts, and means adapted to be displaced by the passage of the frame as the frame moves forward and adapted to return to operative position for pressing said springs inwardly for permitting the insertion of said blank parts.

19. A box blank making machine comprising a frame adapted to receive the blank parts, means for moving said frame forward, flat springs mounted on said frame and extending diagonally outwardly into the position to be occupied by certain of said blank parts, and discs between which said springs are compressed for permitting the insertion of said blank parts as the frame moves forward.

20. A box blank making machine com-

prising a frame adapted to receive the blank parts, means for moving said frame forward, flat springs mounted on said frame and extending diagonally outwardly into the position to be occupied by certain of said blank parts, yieldingly-mounted arms adjacent to the path of said frame, and means mounted on said arms adapted to be displaced by the passage of the frame and adapted to return to operative position for pressing said springs inwardly for permitting the insertion of said blank parts.

21. A box blank making machine comprising a frame adapted to receive the blank parts, means for moving said frame forward, flat springs mounted on said frame and extending diagonally outwardly into the position to be occupied by certain of said blank parts, yieldingly mounted arms adjacent to the path of said frame, and discs revolvably mounted on said arms adapted to be displaced downwardly by the passage of the frame and adapted to return to operative position for compressing said springs for permitting the insertion of said blank parts.

22. A box blank making machine comprising a frame adapted to receive the blank parts, means for moving said frame forward, flat springs mounted on said frame and extending diagonally-outwardly into the position to be occupied by certain of said blank parts, counterbalanced arms pivotally mounted adjacent to the path of said frame, and means mounted on said arms adapted to engage said springs and to displace them for permitting the insertion of said blank parts as said frame moves forward.

23. A box blank making machine comprising a frame adapted to receive cleats and other blank parts, means for moving said frame forward, flat springs mounted on said frame and extending diagonally into the position to be occupied by said cleats, and means acting automatically as the frame moves forward for displacing said springs for permitting the insertion of said cleats.

24. A box blank making machine comprising a magazine for blank parts, a conveyor for forwarding past said magazine a succession of frames adapted to receive such blank parts therefrom, and means arranged to operate to stop said conveyor in case the operator fails to place a frame on said conveyor in advance of said magazine, and to be rendered inoperative by a frame in such position.

25. A box blank making machine comprising a magazine for blank parts, a conveyor for forwarding past said magazine a succession of frames adapted to receive such blank parts therefrom, means for intermittently driving said conveyor, and means arranged to operate to throw said driving means out of operation in case the operator

- fails to place a frame on said conveyor in advance of said magazine, and to be rendered inoperative by a frame in such position.
26. A box making machine comprising a conveyor for forwarding a succession of frames each adapted to receive the blank parts in position for stapling, pawl and ratchet mechanism for driving said conveyor, a shield movably mounted adjacent to said ratchet, and automatically acting means for moving said shield into position between said ratchet and said pawl in case the operator fails to place said frames in normal position on said conveyor.
27. A box blank making machine comprising a conveyor for forwarding a succession of frames each adopted to receive the blank parts in position for stapling, a roller 20 yieldingly mounted below the path of said frame on said conveyor and adopted to be held in lowered position by said frame, and means actuated by the upward movement of said roller permitted by the absence of a frame thereover for throwing said conveyor out of operation.
28. A machine for making box blanks comprising a stapling device, a frame adapted to hold the parts of a blank in position for stapling, means for moving said frame by friction toward said stapling device, means adapted to take said frame from said frictional-feeding means and to forward it positively step by step under said stapling device, and means for varying the speed of one of said forwarding means with respect to the other.
29. A machine for making box blanks comprising a stapling device, a frame adapted to hold the parts of a blank in position for stapling, means for moving said frame by friction toward said stapling device, means adapted to take said frame from said frictional-feeding means and to forward it positively step by step under said stapling device, and means for varying the speed of said frictional feeding means with respect to said positively acting forwarding means.
30. A machine for making box blanks comprising a stapling device, a frame adapted to hold the parts of a blank in position for stapling, an endless belt adapted to carry said frame by frictional engagement therewith toward said stapling device, positively acting means for carrying said frame from said belt to and past said stapling device, and means for varying the speed of said endless belt with respect to that of the positively acting forwarding means.
31. A machine for making box blanks comprising a stapling device, a magazine for blank parts, a frame adapted to receive parts of a blank from said magazine and hold them in position for stapling, a conveyor adapted to carry said frame in a substantially horizontal position under said magazine toward said stapling device, and means carried by the magazine and actuated by the removal of the lowermost part for engaging and moving the lowermost remaining part slightly with respect to the pile for assisting in the automatic feeding of such parts to the frames.
32. A machine for making box blanks comprising a stapling device, a frame adapted to receive the parts of a blank in position for stapling, a conveyor adapted to carry said frame toward said stapling device, and means for feeding blank parts to said frame as it moves forward, said feeding means comprising a hopper adapted to support a pile of parts above said conveyor and spring actuated means carried by the hopper at its forward portion adapted to engage the lowermost one of the pile of parts in the hopper and to move such part slightly backward with respect to the pile.
33. A machine for making box blanks comprising a stapling device, a frame adapted to receive the parts of a blank in position for stapling, a conveyor adapted to carry said frame toward said stapling device, and means for feeding blank parts to said frame as it moves forward, said feeding means comprising a hopper adapted to support a pile of parts above said conveyor, and a pivotally mounted spring-pressed arm on said hopper at its forward portion adapted to be carried forward by engagement with the lowermost one of the pile of parts against the action of the spring and adapted when freed from such engagement to engage the next lowermost one of the pile of parts for moving such part slightly backward with respect to the pile.
34. In a machine for making box blanks, the combination with stapling mechanism, of means for feeding the assembled parts of a blank to such stapling mechanism comprising a frame arranged to receive and hold the parts of the blank in the proper relative position to each other, a conveyor for conducting the frame to said stapling mechanism, intermittently acting mechanism adapted to engage said frame centrally and advance the same from said conveyor past the stapling mechanism, and means for driving said conveyor and said advancing mechanism.
35. In a machine for making box blanks, the combination with stapling mechanism, of means for feeding the assembled parts of a blank to such stapling mechanism comprising a frame arranged to receive and hold the parts of the blank in the proper relative position to each other, a conveyor for conducting the frame to said stapling mechanism, intermittently acting mecha-

nism adapted to engage said frame centrally from below and advance the same from said conveyor under the stapling mechanism, and means for driving said conveyor and said 5 advancing mechanism.

36. In a machine for making box blanks, the combination with stapling mechanism, of means for feeding the assembled parts of a blank to such stapling mechanism comprising a frame arranged to receive and hold the parts of the blank in the proper relative position to each other, said frame having a longitudinally extending rack disposed centrally at the under side thereof, 10 a conveyor for conducting the frame to said stapling mechanism, intermittently acting mechanism adapted to engage said rack for advancing the frame from said conveyor under the stapling mechanism, and means for

driving said conveyor and said advancing 20 mechanism.

37. In a machine for making box blanks, the combination with stapling mechanism, of means for feeding the assembled parts of a blank to such stapling mechanism comprising a frame having a longitudinally extending rack the teeth whereof are spaced apart to correspond with the longitudinal spacing of the staples by which the parts of the blank are to be secured together, a conveyor for conducting the frame to said stapling mechanism, means cooperating with the rack for advancing the frame from said conveyor intermittently past the stapling mechanism, and means for driving said conveyor and said advancing mechanism. 25 30 35

BERT EUGENE HILL.
